TELEVISION TRANSMISSION METHOD

Kurt Schlesinger, Berlin, Germany, assignor, by
mesne assignments, to Loewe Radio, Inc., a
corporation of New York

Application August 13, 1935, Serial No. 36,008
In Germany September 4, 1934

3 Claims. (Cl. 178—7.6)

The present invention relates to television arrangements according to the method of interlaced lines and more particularly to transmitters which transmit film images, the film being intermittently moved image per image like in ordinary film projectors.

The object of the invention are simple means for carrying out an interlaced scanning by a transmitter of the described kind. A further object of the invention are means for producing synchronizing signals causing the ray of the receiving cathode ray tube to describe alternately two respectively three or more interwoven sets of lines.

15 The invention will be best understood by means of the accompanying drawing, in which

Fig. 1 shows the scanning arrangement of a television transmitter according to the invention, whilst

20 Fig. 2 is an example of a device for producing the necessary synchronizing impulses.

By means of a Geneva stop gear 20 well known in the cinematographic art the film 6 is moved only upon change of image, and then to the extent of a complete image length. Thus the film is stationary for nearly $\frac{1}{25}$ sec., and during this time the transmission of two-part-images (frames) is executed. The part of the film within the film gate 21 is illuminated by means of a light source 18 and a mirror 19 or similar arrangements and is projected by means of the optical system 13 on the image field of an ordinary scanning disc 10 having one spiral of e. g. 90 apertures. The disc rotates at 3000 R. P. M., accordingly performing two complete revolutions per image. A photo-cell 15 arranged behind the disc 10 would record the same 90-line image twice in succession if care were not taken for the necessary displacement of the lines. This is accomplished optically by a plano-parallel plate of glass 16 of approximately 5 mm. thickness, which is, for example, by a polarized magnet 17 thrown backwards and forwards between the two positions indicated by dotted lines with a frequency of 50 per second. Accordingly the light rays are displaced at a certain amount upwards respectively downwards, each for $\frac{1}{50}$ of a second. This amount is by adjusting the amplitude of the oscillations of 16 made equal to the width of a line. The operation of the magnet is preferably performed in synchronous fashion by the alternating current which feeds the disc motor, if necessary through the medium of a phase shifter, and the magnet is so adjusted that it moves over

in less than a line period and then remains stationary.

The described arrangement may easily be varied for a threefold or fourfold interlaced scanning or may be replaced by another equivalent optical arrangement.

The receiver consists of a cathode ray tube provided with a line relaxation oscillator producing 90 lines per image and a frame relaxation oscillator producing 50 frames per second. The desired interlaced image is obtained if the frame synchronizing impulses are not isochronous but are given by the transmitter with a time displacement corresponding to a line.

Fig. 2 shows a simple arrangement on the transmitter for producing suitable impulses.

It consists in disc 85 with two projections 86 and 87 which, performs one revolution per image change, i. e. 25 revolutions per second. The projections 86 and 87 are not exactly opposite to each other but displaced to the extent of an angle δ which corresponds exactly to half the period of a line. The said projections interrupt a bundle of light which is furnished by a special light source or derived from the light source 18 (Fig. 1), directed sharply on the same and consequently upon a photo-cell (not shown). With an arrangement of this kind there may be produced through the medium of an amplifier the desired anisochronous impulses and superposed to the image transmission. An impulse siren of this kind may be employed as auxiliary apparatus for existing systems, in which heretofore symmetrical impulses have been produced, and would immediately place existing transmitters of this kind in a position to perform transmission according to the group-displacement method, whereby all cathode ray receivers would participate in the proper fashion in a transmission of this kind if the period of their frame relaxation oscillators is increased from 25 to 50.

I claim:

1. In a television transmitter an arrangement for scanning a film in interlaced lines comprising means for intermittently moving said film through a film gate image per image, a scanning disc having a spiral of apertures and rotating at twice the image frequency, a lens system projecting an image of said film upon the scanning area of said disc and a plano-parallel glass plate disposed between said film and said lens system and means for turning said glass plate suddenly twice per image change by a small angle for displacing said projected image to and fro by the width of a line.

2. In a television transmitter an arrangement for scanning a film in interlaced lines comprising means for intermittently moving said film through a film gate image per image, a scanning disc having a spiral of apertures and rotating at twice the image frequency, a lens system projecting an image of said film upon the scanning area of said disc and a plano-parallel glass plate disposed between said film and said lens system and means for turning said glass plate suddenly twice per image change by a small angle for displacing said projected image to and fro by the width of a line, said means for turning the glass plate consisting of a polarized magnet fed by an alternating current of image change frequency.
3. In a television transmitter an arrangement for scanning a film in interlaced lines comprising

means for intermittently moving said film through a film gate image per image, a scanning disc having a spiral of apertures and rotating at twice the image frequency, a lens system projecting an image of said film upon the scanning area of said disc and a plano-parallel glass plate disposed between said film and said lens system and means for turning said glass plate suddenly twice per image change by a small angle for displacing said projected image to and fro by the width of a line, and an arrangement for producing the necessary anisochronous impulses consisting of a light chopper rotating at the image change frequency and adapted to produce light impulses at intervals differing from each other alternately by a line period. 5 10 15
